METHOD AND APPARATUS FOR
DISTILLING OILSWheaton W. Kraft, East Orange, N. J., assignor
to The Lummus Company, New York, N. Y., a
corporation of Delaware

Application February 14, 1933, Serial No. 656,677

2 Claims. (Cl. 196—94)

The present invention relates to methods and apparatus for distilling oils.

One method of distilling a crude oil to divide it into a number of constituent fractions is to heat the oil in a restricted stream and then to introduce it into a vaporizing column in which a large proportion of the components vaporize under the contained heat of the mixture. Steam may be introduced into the column to facilitate vaporization of the lighter constituents. The residue, which consists of heavy lubricating oil and/or asphaltic material, is withdrawn from the bottom of the column and the vapors pass upwardly through a series of sections of rectifying decks by which the vapors are fractionated into a number of products. One disadvantage of this method is that the large number of decks necessary for fractionation to the several products introduces a back pressure in the vaporizing zone, thereby requiring excessive temperatures or excessive quantities of steam to effect the initial vaporization of all but the heavier components of the oil.

The principal object of the present invention is to provide a method and apparatus for distilling oils in which the stripping of the residue may be effected at minimum temperatures and without any substantial back pressure on the oils being vaporized. With this and other objects in view, the present invention consists of the method and apparatus hereinafter described and particularly defined in the claims.

The accompanying drawing is a diagram of the preferred apparatus for practising the present invention.

The crude oil, which may comprise a Pennsylvania crude, is heated in a restricted stream, as in a pipe still 2, to a temperature sufficient for vaporization of all but the heaviest lubricating oils. This temperature should be below the cracking point and is preferably between 700 and 725° F. The oil thus heated is discharged into a vaporizing chamber 4 of a column 6. The vapors immediately evolved upon the release of pressure rise through the column and the residue is withdrawn from the vaporizing chamber by a pipe 8 and introduced into a stripping section 10. The stripping section 10 may comprise a separate column 11 preferably formed in the base of the column 6, being separated therefrom by an imperforate deck 12.

The vapors pass upwardly through a collecting deck 14 having an upstanding vapor pipe 16, and thence into a rectifying section 18 including a number of decks for promoting contact be-

tween ascending vapors and descending liquid. These decks are diagrammatically illustrated in the drawing, but preferably comprise boiling cap decks for promoting suitable contact between the vapors and liquid. The vapors pass from the section 18 through a plurality of rectifying sections indicated at 20, 22, and 24, each comprising a plurality of suitable contact decks. At the bottom of each of the rectifying sections 20, 22 and 24 is a stripping section 26 comprising a collecting deck 28 having an overflow pipe 30 leading to the section next below. A vapor pipe 32 extends upwardly from the collecting deck. Each stripping section is provided with annular decks 34 surrounding the vapor pipe and steam 15 is introduced into the bottom of the section by a pipe 36.

The vapors, after passing the final rectifying section 24, are condensed in a condenser 38, the final condensate is decanted from the water, and a part is withdrawn as a product through the valved pipe 40, the remainder passing as reflux through the pipe 42 to the top of the column. Water, which comprises the condensate of the steam introduced in the several stripping sections, is withdrawn at 44.

The collecting deck of each stripping section is provided with a draw-off pipe for removal of controlled stripped products rectified in the sections 24, 22, and 20, these draw-off pipes being indicated at 46, 48 and 50 respectively. In addition, unstripped products may be withdrawn from intermediate decks. For example, valved draw-off pipes 52 and 54 are provided at intermediate decks of the rectifying section 24. Similarly, draw-off pipes 56 and 58 are connected with the stripping section 22, and pipes 60 and 62 connected with the stripping section 20.

In the distillation of a Pennsylvania crude oil, a gasoline of about 300° end point is withdrawn at 40, a gasoline of about 400° end point from either or both of the pipes 52 and 54, a stripped kerosene from the draw-off 46, a fuel oil from the pipe 56 or 58, a stripped gas oil from the pipe 48, a wax distillate from the pipe 60 or 62, and a stripped light lubricating oil from the draw-off 50. The lowermost collecting deck 14 is provided with a draw-off 64, to be presently described.

The residue from the upper column which passes to the section 10 through the pipe 8, comprises the heavy lubricating oil, together with a small quantity of intermediate components that are present by reason of the equilibrium existing between vapors and liquid in flash vapor-

zation. In the section 10, the oil descends over decks which are preferably of the usual boiling cap construction and steam is introduced into the bottom of the section by a pipe 66. The stripped heavy lubricating oil is withdrawn from the bottom of the section 10 by a pipe 68. Vapors from the section 10 are conducted by a vapor pipe 70 to be condensed. Preferably, the condensation is effected by passing the vapors through a surface condenser 72 maintained at a temperature to condense nearly all of the oil without any condensation of steam and by passing the remaining vapors to a scrubber 74 where they are contacted with water admitted at 76. The purpose of the combination of the surface condenser and the scrubber is primarily to prevent condensation of steam with the oil whereby corrosive materials might be formed. As a result, the corrosive materials are localized in the scrubber 74 which may be made of such construction as to withstand corrosion. Since the oil vapors admitted to the condenser 72 are the intermediate and heavier vapors of the crude, they combine to only a small extent with steam and hence, all but a small quantity can be condensed in the surface condenser 72 without condensation of steam. The small amount of oil passing over to the scrubber 74 is too small to permit the formation of undesirable emulsions with the large volume of water present and thus a complete and effective recovery of these intermediate oils is obtained.

The ultimate material from the condenser 12 and the scrubber 14 may be obtained as a product. However, since these materials have no definite controlled range of boiling points, it is preferable to pass them by the pipe 78 into the column 6 above the point of the main feed. In the drawing, the pipe 78 is shown as leading into one of the decks of the lowermost reflux section 18. In this section, the return liquid is contacted with the ascending hot vapors and a division of the component materials is effected. In addition to the effect of refluxing the slop cut, the introduction of material by the pipe 78 into the section 18 performs an important function in the operation of the column as a whole. It will be understood that the removal of a number of side products from the upper portions of a column necessarily depletes the supply of reflux in the lower section. The diminution of reflux is therefore most apparent in the bottom section 18, wherein a considerable supply of reflux is necessary for the suppression of the heavy cylinder stock components, which, like the lighter components in the residue from the flashing operation, are present in the vapors by reason of the equilibrium existing between vapors and liquid in flash vaporization. Accordingly, the return pipe 78 is preferably introduced into the deck on which the composition of the reflux naturally existing in the column is approximately the same as that of the re-introduced slop cut. Accordingly, adequate reflux is provided for suppression of the heavy ends and, since the return of a light overhead fraction to the top of the column normally constitutes the sole source of reflux, the amount of this light material required may be very considerably reduced.

The composition of the materials withdrawn from the several draw-offs is controlled by the reflux which courses downwardly through the column. The descending liquid is ultimately collected on the deck 14, and since this material has not been subjected to a stripping action, it

comprises a slop cut, which is ordinarily useful only as a cracking stock. This material may be drawn off at 64 and passed through a pipe 80 to one of the decks of the stripping section 10, wherein it is subjected to the action of the steam entering through the pipe 66. As a result, any heavy residual components contained in the slop cut ultimately find their way into the residue which is withdrawn through the pipe 68 and any lighter materials are passed through the pipe 70 to be condensed in the condenser system and returned to the column for further division. By virtue of contact with the hot vapors rising from the vaporization chamber, the condensate so returned is stripped of components belonging in the next lighter fraction, said components passing upwardly with the vapor to the column section above. The vaporization of these lighter components from the returned condensate results in a corresponding condensation from the vapors of heavier components belonging in the residue.

It will be seen that the residual material withdrawn at 68 is a controlled product from which substantially all components having boiling points below a predetermined value have been removed by the primary flash vaporization in the chamber 4 and by the secondary action of steam in the section 10.

The overhead product is a gasoline of controlled end point determined by the rectification in the reflux zone 24. The side products withdrawn at 46, 48 and 50 are controlled products having initial and end points determined by the action of steam in the respective stripping sections and by the controlled reflux in the rectifying sections. The materials withdrawn at the intermediate draw-offs (52, 54, 56, 58, 60 and 62) are products having boiling points intermediate to those of the stripped side products. 40

The material withdrawn at 64 contains some of the heavy lubricating components that come over in the flash vaporization, together with some intermediate materials, such as light lubricating oils. This is a slop cut that includes components not separated into the other more sharply defined cuts. By introducing it into the section 10, it is subjected to the action of the steam and the components lighter than the desired residue are removed, while the remaining heavy components are passed into the residue. All of the components lighter than heavy lubricating oil which find their way into the section 10, either through the pipe 8 or the pipe 80, are concentrated as a slop cut in the condenser system 72, 74, and by continuously returning this slop cut to the column by pipe 78 as previously described, the components constituting said cut will eventually be removed in controlled products either through the pipe 50 or the pipe 68. 45 50 55 60

In the usual process, the initial vaporization with steam occurs in the main column. According to the present invention, the initial vaporization, without steam, in the chamber 4 effects removal of the greater part of the intermediate and light oils, and the remainder of said oils is removed in the section 10. It is the vaporization of the last remnants of the intermediate and light oils that usually offers the greatest difficulty, and frequently requires either excessive heating or inordinately large quantities of steam. Although the overhead condenser may be at atmospheric pressure, the vaporizing zone may be at a pressure several pounds above atmosphere, due to the back pressure introduced by the decks 75

in the rectifying zones. In the present invention, the steam stripping section 10 is under a considerably reduced pressure, as compared with the pressure in the main column, and the removal of the final remnants of the intermediate and light oils can be effected with a saving of steam, and without the necessity of initially heating to an unsafe temperature.

Having thus described the invention, what is claimed is:

1. The method of distilling oils which consists in heating the oil in a restricted stream, introducing the heated oil into a vaporizing zone to evolve vapors by flash vaporization, passing the vapors from the vaporizing zone through a rectifying zone, contacting the vapors with descending liquid in the rectifying zone, collecting and withdrawing reflux liquid at the bottom of the rectifying zone while preventing passage of reflux into the vaporizing zone, passing the residue of the vaporizing operation and the withdrawn reflux to a stripping zone unconnected with the vaporizing zone, introducing steam into the stripping zone, condensing the oil vapors from the stripping section by surface condensation with-

out condensing the steam, condensing the remainder of the steam-oil mixture by direct contact with water in sufficient quantity to prevent formation of emulsions, and passing oil condensate to the rectifying zone.

2. Apparatus for distilling crude oil comprising a heater, a column having a flash vaporizing chamber, a rectifying section above the vaporizing chamber, means for passing reflux liquid downwardly through the rectifying section, a stripping section unconnected with the column, means for passing residue from the column to the stripping section, means for introducing steam into the stripping section, a collecting deck immediately above the vaporizing chamber to collect reflux liquid as a slop cut and constructed to prevent passage of liquid into the vaporizing zone, means for passing the slop cut to the stripping section, a surface condenser for condensing the oils from the stripping section without condensation of steam, a scrubber for condensing the steam and any remnant of oil therewith, and means for passing oil from the condenser and scrubber to one of the rectifying sections.
